BOAT

Robert R. Hammond, 6802 Daugherty, Austin, Tex.

Filed Apr. 8, 1959, Ser. No. 55,415

Term of patent 14 years

(Cl. D71—1)

FIG. 1.

FIG. 2.

FIG. 3.

FIG. 4.

Fig. 1 is a top plan view of a boat embodying the new design;

Fig. 2 is a side elevation thereof;

Fig. 3 is a perspective view of the boat, taken from the side and rear thereof; and

Fig. 4 is a rear elevational view thereof.

The dominant features of the design reside in full lines.

I claim:

The ornamental design for a boat, substantially as shown and described.
